UNITED STATES PATENT OFFICE.

EMIL G. STEIN, OF LOS ANGELES, CALIFORNIA.

WOODWORKING BIT.

1,410,534.

Specification of Letters Patent. Patented Mar. 21, 1922.

Application filed January 18, 1921. Serial No. 438,173.

To all whom it may concern:

Be it known that I, EMIL G. STEIN, a citizen of the United States, residing at Los Angeles, in the county of Los Angeles and 5 State of California, have invented new and useful Improvements in Woodworking Bits, of which the following is a specification.

It is the object of this invention to provide a bit particularly adaptable as a wood 10 working bit for boring holes in thin veneer and the like.

The invention provides a construction wherein the axial screw at the end of the bit is countersunk so that the bit blades 15 will operatively engage the surface of the work immediately after the point of the screw has first engaged the work. By this arrangement the blades of the bit will have cut into the surface of the work by the 20 time that the screw of the bit has penetrated the work, and the liability of splitting the work is thereby eliminated.

The invention will be readily understood from the following description of the 25 accompanying drawings in which:

Figure 1 is a side elevation of a bit constructed in accordance with the invention.

Figure 2 is a similar view of the lower 30 end of the bit taken in a plane at right angles to that of Fig. 1.

Figure 3 is a bottom plan view of the bit as shown in Fig. 2.

Figure 4 is a plan view of the work engaged by the bit showing the starting of a 35 hole bored therein by the bit.

Figure 5 is a transverse section on the line 5—5 of Fig. 4.

The improved bit consists of a usual shank 1 having the upper end 2 adapted to 40 be engaged in a usual socket, and also provided with a usual spiral rib 3, which at its lower end forms one of the radial cutting blades of the bit. The other radial cutting blade of the bit is formed upon a rib 4 45 arranged at the lower end of shank 1 in usual manner between the two lowermost convolutions of spiral 3.

The lower end of shank 1 terminates in a usual axial lead screw 5 adapted to first 50 engage the work when the bit is brought into operative position. In bits as heretofore constructed, this lead screw is projected a considerable distance beyond the blades formed on the lower edges of ribs 3 55 and 4, and, as a consequence, when boring

through thin veneer and the like, the axial aperture formed by this screw through the work before the blades of the bit engage the work, has tended to cause splitting of the veneer. In the present construction, the 60 blades of the bit are so arranged as to engage the work immediately after the point of lead screw 5 is brought into operative position.

As an instance of this arrangement, the 65 ends of ribs 3 and 4 are shown spirally prolonged downwardly beyond the upper end of lead screw 5, as shown at 6, and said prolongations preferably taper to points 7 at the outer peripheries of the ribs. These 70 points are in a plane but slightly above the point of lead screw 5, and, as a consequence, when the bit is employed for boring through thin veneer or the like, as shown at V in Fig. 4, as soon as the screw 5 has started an 75 axial aperture A, the blades of the bit will start an annular recess R and thereby prevent splitting of the veneer.

It will be understood that the usual longitudinally depending blades 8 are formed 80 upon the under sides of the ends of ribs 3 and 4 at the outer peripheries of said ribs, and these blades are preferably spaced back along the ribs from the prolongations 6 of the same, and, as a consequence, the annular 85 recess R started by the blades of the bit immediately after screw 5 engages the work, will be cut by the tapering and pointed prolongations of the respective ribs which extend downwardly into a plane which is 90 spaced but slightly above the point of the lead screw.

By reference to Fig. 5 it will be seen that at the start of a hole bored by the bit, the annular recess R will be cut through 95 the work nearly as deep as the axial aperture A formed by lead screw 5, so that by the time the axial aperture has been formed entirely through the work, the annular recess R will also have penetrated nearly the 100 full thickness of the work, thereby reducing the liability of splitting of the relatively thin material in which the aperture is formed.

I claim as my invention:

A wood working bit comprising a shank, an axially disposed lead screw depending from the lower end of said shank, a pair of oppositely disposed radially arranged blades extending downwardly and out- 110

wardly from the lower portion of the shank, the lower outer ends of which blades occupy a plane slightly above the plane occupied by the point of the lead screw, and 5 vertically disposed cutting blades depending from the outer portions of the radially disposed cutting blades, the lower edges of

which vertically disposed blades occupy substantially the same horizontal plane with the lower outer ends of the radially disposed cutting blades. 10

In testimony whereof I have signed my name to this specification.

EMIL G. STEIN.
